SANDFORD C. PEEK, OF EAST AURORA, NEW YORK

GAME DEVICE

Application filed February 4, 1928. Serial No. 251,986.

This invention relates to game devices, and has for an object to provide an improved and simple game device for the entertainment of young and old.

5 A further object of the invention is to provide an improved game device which will be entertaining to children; which will train them in strategy; which will hold their interest; and which will be relatively simple, 10 durable and inexpensive.

Various other objects and advantages will be apparent from the following description of one embodiment of the invention, and the novel features will be particularly pointed out hereinafter in connection with the appended claims.

In the accompanying drawings:—

Fig. 1 is a side elevation of a device constructed in accordance with the invention;

20 Fig. 2 is an end elevation of the same;

Fig. 3 is a longitudinal, sectional elevation of the same, the section being indicated as approximately along the line 3—3 of Fig. 4;

25 Fig. 4 is a sectional plan of the same;

Fig. 5 is a fragmentary, longitudinal, sectional elevation of a portion of the same, with the section taken approximately along the line 5—5 of Fig. 4; and

30 Fig. 6 is a partial, transverse, sectional elevation of the same, the section being taken approximately along the line 6—6 in Fig. 3.

In the illustrated embodiment of the invention, the game device includes a cabinet or enclosure 1, having a top wall 2 and side walls 3. A leg or prop 4 is hinged, as by pivots 5, between the side walls 3 at one end thereof so as to support the enclosure or cabinet in an inclined position when the other end of the cabinet or enclosure is supported directly upon the surface upon which the leg or prop 4 is placed. A bar 6 extending across between the side walls 3 at the upper end of the enclosure limits the outward movement of the prop or leg 4 materially beyond a straight-out position, and therefore when the enclosure is supported upon a surface by this prop, the prop or leg 4 will be slightly inclined and held against

the cross bar 6 by the weight of the cabinet. This provides a simple and stable support for holding the enclosure in an inclined position, yet the prop or leg 4 may be swung upwardly into the enclosure for compactness when the device is not in use.

A plate or partition 7 is mounted between the side walls 3 at a point spaced below the top 2, so as to extend lengthwise of the enclosure from the higher open end thereof. 60 This plate 7 extends preferably to a point beyond the mid length of the enclosure and at its lower end has a cross groove 8 in the corner edge of its upper face. A second plate 9 is disposed between the side walls 3 at the lower end of the enclosure and this plate extends from the lower end upwardly in a direction lengthwise of the cabinet to a point in proximity to but spaced from the lower end of the plate 7 so as to provide between the plates 7 and 9 an open gap or aperture 10. The plane of the upper face of the plate 9 is slightly below the plane of the upper face of the plate 7, for a purpose which will appear shortly. Another plate 75 11 is also mounted between the side walls 3 of the enclosure at the lower end of the cabinet extending from a point in proximity to the bottom edge of the cabinet or enclosure, upwardly in an inclined direction beneath 80 and beyond, but spaced from the open gap or aperture 10. A block 12 mounted between the side walls 3 and upon the upper end of the plate 11 provides an inclined runway leading from the plate 11 to the lower 85 end edge of the plate.

A plurality of flat strips 13 are disposed side by side upon the upper face of the plate 9 so as to be shiftable independently of one another upwardly along the plate 9 and into 90 the cross groove 8. When so shifted, these strips 13 serve as bridges covering the aperture 10, the thickness of the plates 13 being the same as, or slightly less than, the groove 8, so that the strips 13 when across the gap 95 will serve as continuations of the runway formed by the upper surface of the plate 7. When the strips 13 are shifted downwardly, they will be withdrawn from over the gap 10, and the inclined surface of the block 12 will 100

form the continuation of the runway formed by the upper surface of the plate 7, this continuation of the runway thus formed merging into the upper surface of the plate 11. It will thus be observed that the runway formed by the plate 7 may be considered as divided at a point intermediate the ends of the cabinet or enclosure into two paths, one of which is down the inclined surface of the block 12 and upon the plate 11, and the other of which is along the strips 13 and down the upper surface of the plate 9. The strips or bridges 13 are in effect switching means for directing along either of these paths any objects moving down the runway. The passages within the cabinet which have the runways for the floor thereof are in reality tunnels, the tunnel having as its bottom the plate 7 being the main tunnel and dividing into two separate tunnels at the gap 10.

A cross bar or plate 14 may be provided between the side walls 3 at the lower end of the enclosure or cabinet and at the lower edge of the plate 9 to form a step for objects passing over the plate 9. A similar cross bar 15 at the lower edge of the plate 11 serves as a stop for objects passing down the block 12 and over the plate 11. These bars 14 and 15 are spaced apart, however, to permit access to the space between the plates 9 and 11 through the lower end of the cabinet. The chamber at the lower end of the enclosure or cabinet, formed by the cross bar 14, the plate 9, the side walls 3 and top wall 2, may be considered as a compartment or tunnel A serving as the terminus of one of said paths, and the space in the lower end of the enclosure or cabinet between the plates 9 and 11 forms another tunnel or compartment B serving as the terminus of the other path of said runway. By selectively adjusting the strips or bridges 13 across or free of the gap 10, any objects moving down any portion of the runway formed by the plate 7 will be directed into one or the other of the compartments A and B depending upon the setting of the bridge 13 in that portion of the runway.

To guide the strips or bridges 13 in their sliding movements and also in order to divide the runway into a plurality of separate roadways or tracks, a plurality of rails 16 may be provided upon the upper face of the plate 7 in parallel spaced relation to one another and extending from the upper end of the cabinet or enclosure along the plate 7 preferably beyond the gap 10, and either to, or in proximity to, the lower end of the enclosure. The strips or bridges 13 nicely fill the spaces between the rails at the lower end of the enclosure, and the rails guide these strips in their sliding movements, and also prevent displacement of these strips or bridges crosswise of the enclosure or cabinet. The strips or bridges 13 thus constitute individual switches or bridges controlling the section of the gap 10 in that

particular roadway in which it slides. Each section of the gap is therefore a sub-gap, opening or aperture in the floor of the tunnel formed between the top and sides of the enclosure and the plate 7.

An L-shaped strip 17 may be secured edge-wise of one arm against the outer face of one of the side walls 3, so as to form with that side wall a return trackway 18, and this strip 17 when the cabinet or enclosure is supported in its inclined position by the prop or leg 4, is also inclined to the horizontal but in a direction reverse to the inclination of the plate 7 in the enclosure. Thus the trackway 18 on the outside of the cabinet serves as a means for returning to the higher end of the enclosure any objects which have passed down the interior of the enclosure in a manner to be explained. The top wall 2 may terminate shortly above the lower end of the cabinet so as to provide an opening at the lower end of the enclosure through which access may be had to remove objects from the compartment A and to permit of the selective setting of the bridges or strips 13. Access to the lower compartment B is obtained through the lower end of the cabinet between the cross bars 14 and 15.

The top wall 2 of the enclosure or cabinet serves to screen or conceal from a player at the higher end of the cabinet a view of the gap 10, so that this player at the higher end of the cabinet will not be able to observe the positions or settings of the strips or bridges 13, and therefore will be unable to know whether an object conducted down any particular roadway will pass into the upper or lower compartment. To further screen the gap 10 from the view of this player at the higher end of the cabinet, a curtain 19 of suitable flexible material, such as cloth or textile material, may be secured to the top wall 2 and suspended across the tunnel formed in the enclosure between the top wall 2, the side walls 3 and the plate 7, and this curtain 19 may be provided with a plurality of slits 20 extending from the lower edge upwardly for some distance so that the curtain will offer little resistance to objects passing down the tunnel and at the same time will serve as an effective vision screen across the tunnel.

The objects or articles which are to be passed down the roadways in the use of this cabinet, may be of any suitable type which will roll, move, or slide freely down the tunnel, such as marbles or balls of different sizes, or other rolling objects such as miniature or toy vehicles. For example, a plurality of small toy trucks 21 and one or more small toy automobiles 22 may be utilized as the moving objects which are conducted through the tunnel. A plurality of small dolls or figures representing soldiers may be provided and loaded into the trucks in order to add interest

to the playing of the game, especially for small children.

In the use of the illustrated embodiment of this improved game device, let it be assumed that there are two trucks 21, one toy automobile 22 and four tracks on the inclined runway. The cabinet is placed upon a suitable surface or floor in an inclined position as shown in Figs. 1, 2 and 3. One player is 10 stationed at the higher end of the cabinet and another player at the lower end. The player at the higher end of the tunnel takes possession of the trucks 21 and the automobile 22, and is given a number of toy soldiers. The 15 player at the lower end of the cabinet places his hand within the lower end of the enclosure or cabinet manipulates the strips or bridges 13 in a selected manner, known only to himself, so as to bridge the gap 10 of say 20 two of the tracks or roadways and to leave the gaps in the other tracks or roadways open. The player at the higher end then starts the trucks 21 loaded with soldiers and the automobile 22 separately or together down any 25 of the roadways which he may select, with the result that the trucks and auto will pass into one terminal compartment or the other depending upon the position of the bridges or switches 13 of the roadways utilized, that is, 30 depending upon whether or not the bridge or switch 13 for each roadway or track used is in bridging or open relation with the gap in that track.

In Fig. 4 one of the trucks is illustrated as 35 passing downwardly through the gap 10 into the lower compartment B, and another truck as passing over one of the bridges or switches 13 into the upper compartment A. The automobile 22 has previously passed down the 40 same roadway into the upper compartment A. The automobile 22 preferably has a figure therein, which may, for the purpose of creating interest, be considered a general, and the soldiers in the trucks may be considered as the army. The player at the higher end of 45 the cabinet endeavors to select the roadways which will conduct the trucks and the auto into the upper compartment A which may, for the purpose of play, be designated as the fort to be taken. The lower compartment B 50 may be designated as the grave yard, and if the trucks or auto pass into the grave yard through gap 10, they may be considered as killed and do not count, but if they pass into 55 the upper compartment A or the fort, the player in the upper end is given a numerical credit depending upon the number of soldiers so entering the fort, the entry of the general (automobile 22) into the fort giving a player 60 a greater number of credits than the entry of a truck load of soldiers.

The player at the higher end of the cabinet is given a certain number of attempts or plays, and for each such play or attempt, 65 the player at the lower end may operate the

switches or bridges in a secret manner unknown to the player at the higher end of the cabinet. After the player at the higher end of the cabinet has made the allotted number of attempts or plays, the players change 70 positions, and the game is proceeded with as before. The trucks and auto may be returned to the higher end of the cabinet by rolling them down the trackway 18 at one side of the cabinet. Inasmuch as the tunnels through 75 which the trucks and auto are conducted is enclosed, and because of the curtain 19, the player at the lower end of the cabinet 1 cannot observe which tracks are being utilized by the player at the higher end of the 80 cabinet, and the player at the higher end cannot observe the condition of the switches or bridges at the lower end of the cabinet. Such a game device has been found to be very entertaining to both children and adults, and 85 aids in developing in the players the principles of strategy. The device is compact, simple, durable, and relatively inexpensive.

It will be understood that various changes 90 in the details which have been herein described and illustrated in order to explain the nature of the invention, may be made by those skilled in the art within the principle and scope of the invention as expressed in the appended claims.

I claim as my invention:—

1. A game device comprising a runway along which objects may move from one end thereof, selectively operable switching means arranged at a point spaced from said one end, for diverting into different paths any objects moving along said runway from said one end, and means for screening said switching means from the sight of a player at said one end of the runway.

2. A game device comprising an inclined tunnel divided into separate branches at a point between its ends, and switching means at the division point and selectively and variably shiftable to divert into one of said branches any objects moving down selected and variable portions of said tunnel, and to divert into the other of said branches any objects moving down remaining portions of said tunnel.

3. A game device comprising a tunnel divided into separate branches at a point between its ends, switching means at the division point and selectively and variably shiftable to divert into one of said branches any objects moving along selected and variable portions of said tunnel from the entrance end thereof, and to divert into the other of said branches any objects moving along remaining portions of said tunnel, and a yieldable screen between said division point and the entrance end of said tunnel for obstructing a view of said switching means from the entrance end of said tunnel.

4. A game device comprising a tunnel di-

- vided into separate branches at a point between its ends, switching means at the division point and selectively and variably shiftable to divert into one of said branches any 5 objects moving along selected and variable portions of said tunnel from the entrance end thereof, and to divert into the other of said branches any objects moving along remaining portions of said tunnel, and a curtain slit 10 vertically and suspended across the tunnel at a point between said switching means and the entrance end of said tunnel for permitting the passage thereby of objects passing along the tunnel and for obstructing a view 15 of the switching means from the entrance end of said tunnel.
5. A game device comprising an elongated tunnel, means for supporting said tunnel in an inclined position, a compartment beneath the tunnel and opening upwardly through the floor of the same at a point between the ends of the tunnel, and bridge means cooperating with the floor of the tunnel and shiftable to bridge said opening at 20 selected and variable points in the width of said tunnel, whereby objects moving down certain portions of the floor of the tunnel will pass through said opening into said lower compartment and other objects moving down 25 the other portions of the floor of said tunnel will be guided over said opening to the lower end of the tunnel.
6. A game device comprising an inclined tunnel having an opening across the floor 30 thereof at a point between its ends, said tunnel having a compartment below the lower end thereof and communicating with said opening in the floor thereof, and a plurality of members arranged side by side and bridging said opening, and individually and selectively shiftable into and out of bridging positions, whereby objects moving down selected portions of the floor of said tunnel will pass through said opening into 35 the lower compartment, and objects moving down other portions of the floor of said tunnel will be guided across said opening by said members to the lower end of the floor of the tunnel.
- 50 7. A game device comprising an inclined tunnel having rails extending lengthwise along and dividing the floor of the tunnel into separate roadways arranged side by side, the floor of said tunnel being apertured at a point between its ends to provide an opening in the bottom of each roadway, said tunnel having a compartment below the lower end thereof and communicating with the aperture of said tunnel, and an individual bridge for the opening in each roadway 40 shiftable to cover or uncover its opening independently of the others, whereby objects moving down certain of said roadways may be guided across said openings to the compartment formed by the lower end of said tunnel, and objects passing down the other roadways will pass through said openings into said compartment below the tunnel floor, said individual bridges being accessible for operation by a player at the lower 45 end of the tunnel.
8. A game device comprising an inclined tunnel having rails extending lengthwise along and dividing the floor of the tunnel into separate roadways arranged side by side, the floor of said tunnel being apertured at a point between its ends to provide an opening in the bottom of each roadway, said tunnel having a compartment below the lower end thereof and communicating with the aperture of said tunnel, and an individual bridge for the opening in each roadway 50 shiftable to cover or uncover its opening independently of the others, whereby objects moving down certain of said roadways may be guided across said openings to the compartment formed by the lower end of said tunnel, and objects passing down the other roadways will pass through said openings into said compartment below the tunnel floor, said individual bridges being accessible for operation by a player at the lower 55 end of the tunnel.
9. A game device comprising an inclined tunnel having rails extending lengthwise along and dividing the floor of the tunnel into separate roadways arranged side by side, the floor of said tunnel being apertured at a point between its ends to provide an opening in the bottom of each roadway, said tunnel having a compartment below the lower end thereof and communicating with the aperture of said tunnel, an individual bridge for the opening in each roadway shiftable to cover or uncover its opening independently of the others, whereby objects moving down certain of said roadways may be guided across said openings to the compartment formed by the lower end of said tunnel, and objects passing down the other roadways will pass through said openings into said compartment below the tunnel 60 floor, and a screen supported across said tunnel at a point between said openings and the higher end of said tunnel permitting passage thereby of said objects, and screening said openings from the sight of a player 65 at the higher end of said tunnel.
10. A game device comprising an inclined tunnel divided into separate branches at a point between its ends, switching means at the division point and selectively and variably shiftable to divert into one of said branches any objects moving down selected and variable portions of said tunnel, and to divert into the other of said branches any objects moving down remaining portions of said tunnel, and an oppositely inclined runway extending along said tunnel for returning to the higher end of said tunnel objects which have been passed down said tunnel.
11. A game device comprising an inclined 130

runway dividing into separate branches at a point adjacent its lower end, switching means at said division point and selectively and variably shiftable to divert into one of said branches any objects moving down selected and variable portions of said runway, means for screening said switching means from the sight of a player at the higher end of said runway, and a plurality of rolling objects having distinguishing characteristics.
